UNITED STATES PATENT OFFICE.

ALEXANDER R. KANNÉ, OF BROOKLYN, NEW YORK, ASSIGNOR TO KANNÉ & BESSANT, INC., OF NEW YORK, N. Y., A CORPORATION OF NEW YORK.

DESIGN FOR A SUPPORTING PEDESTAL FOR LAMPS.

Application filed August 24, 1928. Serial No. 27,944. Term of patent 7 years.

To all whom it may concern:

Be it known that I, ALEXANDER R. KANNÉ, a citizen of the United States, residing at 1510 Carroll Street, Brooklyn, in the county of Kings and State of New York, have invented a new, original, and ornamental Design for a Supporting Pedestal for Lamps, of which the following is a specification, particular reference being had to the drawing, forming part thereof.

In the drawings—

Fig. 1 is a view in side elevation, with portions broken away to indicate variation in height, and

Fig. 2 is a top plan view thereof.

I claim:

The ornamental design for a supporting pedestal for lamps, as shown and described.

I affix my signature.

ALEXANDER R. KANNÉ.
